Patented Dec. 6, 1921.

FIG. 1

FIG. 3

FIG. 2.

J. F. KRAUS. INVENTOR
BY *Victor J. Evans*
ATTORNEY

UNITED STATES PATENT OFFICE.

JACOB F. KRAUS, OF PITTSBURGH, PENNSYLVANIA.

OIL-BURNER.

1,399,626.

Specification of Letters Patent. Patented Dec. 6, 1921.

Application filed September 28, 1920. Serial No. 413,294.

To all whom it may concern:

Be it known that I, JACOB F. KRAUS, a citizen of the United States, residing at Pittsburgh, in the county of Allegheny and State of Pennsylvania, have invented new and useful Improvements in Oil-Burners, of which the following is a specification.

This invention relates to oil burners, and more particularly to a burner specially adapted for burning the heavier fuel oils.

One of the main objects of the invention is to provide a burner of simple construction and operation which will insure thorough mixing of the oil with air so as to obtain complete combustion of the oil and produce intense heat. A further object is to provide a burner in which the oil is distributed over a relatively great area and is then subjected to the action of air currents so as to be rapidly evaporated and mixed with the air. Another object is to provide means whereby a whirling movement is imparted to the oil and air so as to insure thorough intermingling and mixing of the same and produce a mixture of uniform consistency. Further objects will appear from the detailed description.

In the drawings:—

Figure 1 is a central vertical sectional view of a burner constructed in accordance with my invention.

Fig. 2 is a section taken substantially on line 2—2 of Fig. 1.

Fig. 3 is a fragmentary plan view of the inner air tube and associated parts.

The burner includes a cylindrical body 1 provided at one end with an enlarged intake socket 2 and at the other end with a squared portion or block 3 which is cored out to provide a nozzle 4.

A tube 5 is supported within body 1 and is secured by set screws 6. This tube is disposed substantially co-axially with body 1 and is provided with an angular strip or thread 7 which is secured to the inner face of the tube and forms helical threads extending about the inner face of the tube. This member 7 serves to impart to air flowing through tube 5 a whirling or rotary motion. The tube is further provided at its forward end with a bent up member which is shaped to form a deflector or spraying plate 8 of substantially flattened V-shape. An oil tube 9 extends through rearward wall 1^a of body 1 and projects into the body above the tube 5, this tube 9 having its inner end re-

duced to form a tapered oil discharge nozzle 10 by means of which the oil is discharged against the inner face of plate 8 at the central portion thereof, this plate serving to divide the oil and to cause it to flow downwardly over and about tube 5.

In practice air is admitted under pressure into member 2 and flows through body 1. Part of this air flows about tube 5 so as to remove the oil which flows over the outer surface of this tube, this oil being rapidly absorbed by the air and intimately mixed therewith. A central current or column of air flows through tube 5 and has a whirling motion imparted to it by the rib or vane member 7. Any oil which is not removed from the outer surface of tube 5 by the air will drip into an arcuate pan 11 which is supported below the forward portion of tube 5 by certain of the set screws 6 and by rivets 12, or in any other suitable manner. Any oil which may drip into pan 11 will be removed by the air flowing through the pan, and this mixture of oil and air, together with the air and oil flowing from about tube 5, will be acted upon by the air column flowing through tube 5, the three air currents converging and intermingling so as to cause thorough mixing of the air and the oil thus producing a readily combustible mixture which insures complete combustion of the oil and the production of intense heat.

What I claim is:

1. In an oil burner, a hollow body, a tubular member supported within said body substantially coaxially therewith, said member being open at both ends and spaced away from the body, the passage formed between the tubular member and the body being open at both ends, and means for discharging oil onto the upper portion of the tubular member.

2. In an oil burner, a hollow body provided at one end with a discharge nozzle, a tubular member supported within said body in spaced relation thereto, means for spraying oil onto the upper portion of the outer surface of said tubular member, and a pan positioned beneath and in spaced relation to the tubular member.

3. In an oil burner, a body provided at one end with a discharge nozzle, a tubular member supported within said body in spaced relation thereto and open at both ends, means for imparting a whirling motion to a current of air flowing through the

tubular member, and means for spraying oil onto the outer surface of said tubular member.

4. In an oil burner, a hollow body, a tubular member supported within said body in spaced relation thereto and provided with an upwardly projecting spraying plate, and an oil supply tube disposed to discharge oil against said plate, said tubular member being disposed substantially coaxially with the body and being open at both ends.

5. In an oil burner, a hollow body, a tubu-

lar member supported within said body substantially coaxially thereof and open at both ends, a plate projecting upwardly from said tubular member, an oil supply tube disposed to discharge oil against said plate, an oil receiving pan supported beneath the lower portion of the tube and spaced away from the same and the body, and means for imparting a whirling motion to air flowing through the tube.

In testimony whereof I affix my signature.

JACOB F. KRAUS.
